ATTORNEY

UNITED STATES PATENT OFFICE.

TATSUJIRO IMAIZUMI, OF SEATTLE, WASHINGTON.

LIFE-BUOY.

1,305,606.

Specification of Letters Patent. Patented June 3, 1919.

Application filed November 6, 1918. Serial No. 261,359.

To all whom it may concern:

Be it known that I, TATSUJIRO IMAIZUMI, a subject of the Empéror of Japan, and resident of the city of Seattle, county of King, 5 and State of Washington, have invented certain new and useful Improvements in Life-Buoys, of which the following is a specification.

My invention relates to life buoys and consists of a life buoy of an improved type of construction in which the flotation is secured by a large number of small cells, each of which is independent of all the others, so far as the retention of the air contained therein, 15 whereby, if some of these become punctured, the remainder are not affected.

The object of my invention is to secure greater safety by the use of cellular flotation members and also to provide means whereby 20 the comfort of the wearer may be promoted by providing foot supports, which are suspended from the buoy.

My invention comprises the novel features which will be hereinafter described and then 25 particularly defined by the claims.

The accompanying drawings show my invention in the preferred form of construction.

Figure 1 shows a buoy in perspective, a 30 portion of the casing and interior parts being broken away so as to better illustrate its construction.

Fig. 2 is a section taken on the plane of the buoy.

Fig. 3 is a perspective, showing in section one of the segment cells, and Fig. 4 shows in perspective, one of the small cup-like cells, which are placed inside of the segment cells.

By my invention I provide a series of 40 small elements which are of a cup-like character, adapted to be nested together, and a series of these segment cells placed end to end so as to form a ring, which ring is enclosed within a canvas or like covering to 45 form the buoy.

One of the small cup-like cells is shown in perspective in Fig. 4. These cells B are made with their sides slightly tapering so that they may be nested together, after the 50 manner shown in two of the segments shown in Fig. 2. The last one of each of these series, being the cell C, as shown in Fig. 2, is

preferably provided with a cover so that it provides its own covering instead of relying upon the next cell to close it.

55

The material of these cells is preferably after the nature of celluloid, ebonite, hard rubber, or the like, which may be made to nest together and to form a tight joint.

The segment cells A may be made of light 60 material of a similar character. These serve to hold the smaller cells B in place and to give a certain measure of stiffness against transverse bending. They prevent such transverse bending occurring at any point 65 except between the segment cells. Therefore, the tightness of the joint formed between adjacent cup cells B is maintained.

A sufficient number of the segment cells A to form a complete circle is provided with 70 a cover G of canvas. Such a buoy is light and also has a sufficient rigidity for all practical purposes.

I prefer to provide a buoy with bands H, 75 two of which, at opposite sides, are provided with eyes, as I, through which are passed the ends of cords J. These cords are intended to depend from the buoy and to be provided with stirrups or loops F, at such a distance below the buoy as to make it convenient to 80 place the feet in these loops and thereby to assist in supporting the body.

To maintain these loops separated sufficiently for convenience, I prefer to connect them by a rigid member or bar, as E, which 85 bar may be made as a small float. This contributes to the convenience of the user, as otherwise the stirrups F would tend, either to separate or to draw together.

I may also provide the buoy with a cord 90 K extending to the same, on its outer periphery, and passing beneath the various bands H. This forms a convenient means for catching and securely retaining a hold upon the buoy.

95

What I claim as my invention is:

1. A life buoy having a ring-like body and a cellular structure for said body formed by cup-like elements nested together.
2. A life buoy having a ring-like body 100 composed of a series of segment cells, and a series of cup-like members nested together with each of the segment cells.
3. A life buoy having a ring-like body

composed of a series of segment cells, and a series of cup-like members nested together within each of the segment cells, the terminal cup at one end of the series being closed.

5 4. A life buoy having a ring-like body composed of a series of closed segment cells

placed end-to-end and a series of nested cup-like elements in each segment cell, and a casing surrounding the whole.

Signed at Seattle, Washington, this 30th 10
day of October, 1918.

TATSUJIRO IMAIZUMI.
